UNITED STATES PATENT OFFICE.

JOHN D. CARDINELL, OF MONTCLAIR, NEW JERSEY.

WATERPROOF ENVELOP.

1,323,578.

Specification of Letters Patent.

Patented Dec. 2, 1919.

Application filed January 23, 1919. Serial No. 272,666.

To all whom it may concern:

Be it known that I, JOHN D. CARDINELL, a citizen of the United States, residing at Montclair, in the county of Essex and State 5 of New Jersey, have invented certain new and useful Improvements in Waterproof Envelops; and I do declare the following to be a full, clear, and exact description of the invention, such as will enable others 10 skilled in the art to which it appertains to make and use the same.

My invention has for its object to provide a protecting envelop for data relating to numerous articles, and to provide novel 15 means for holding the envelop against accidental opening and for attaching it to the article to which it relates. With this object in view, the invention resides in the construction and arrangement herein described 20 and claimed.

Figure 1 of the accompanying drawings is a perspective view showing the invention applied to a shell.

Fig. 2 is a view similar to Fig. 1, showing another manner of attaching the envelop.

Fig. 3 is a perspective view of the envelop before sealing.

Fig. 4 is a transverse section on the plane 30 of the line 4—4 of Fig. 3.

Fig. 5 is a plan view of the blank from which the envelop is formed.

Fig. 6 is a perspective view of a different form of the invention.

35 In the manufacture of the improved envelop, a single blank 1 of waterproof paper or any other preferred material is employed, said blank consisting of a rectangular back area 2, a pair of rectangular flaps 3 integral with the side edges of said back area and adapted to form the front of the envelop, a pair of sealing flaps 4 integral with the ends 40 of the back area 2 and tabs 5 integral with the outer ends of the sealing flaps. As seen

45 in Fig. 5 the edges 6 of the flaps 4 may diverge inwardly and coincide with the ends of the flaps 3 at the points 7, these points being spaced outwardly from the side edges of the back 2. By this provision, seals 8 are 50 provided in the angles between the flaps 4 and 3, but in some instances (see Fig. 6) these seals may be omitted. Either simultaneously with the stamping operation which cuts the blank 1, or at any other suitable time, metal eyes 10 are secured in the

tabs 5, and these tabs are foldable outwardly from the sealing flaps 4, on the weakened lines 11. In some instances, the metal eyes might be eliminated and in lieu thereof openings merely punched through the tabs 5 in 60 which case the latter will be reinforced by paper or the like secured around the openings, but in most cases said metal eyes are preferable.

Upon the lines 12 which separate the 65 back area 2 from the flaps 3, these flaps are folded forwardly into overlapping relation to form the front of the envelop, the two flaps being glued or otherwise suitably secured together. It will be observed by reference to Fig. 2 that after this folding operation, the seals 8 extend beyond the lines 13 upon which the sealing flaps 4 are folded, and that when the flaps 4 are folded upon the envelop front, the seals will be correspondingly folded. When the flaps 4 and 70 seals 8 are now secured to the front of the envelop by means of coatings of glue or other viscous material, the ends of the envelop will be sealed in water-tight manner. 75 The tabs 5 may be bent outwardly from the flaps 4 and the cord 14 by means of which the package 15 is tied, may be passed through the eyes 10 and tied as seen in Figs. 1 and 2. The sealed envelop may contain 80 important data relating to the contents of the article or may contain other subject matter having the same destination, and it will be obvious that the device may be constructed in numerous sizes and of any preferred material. In most cases, the material is waterproofed in some adequate manner but when conditions are encountered which do not require such precautions, they need 85 not of course be taken.

90 The device is of particular advantage for use in connection with shells and projectiles since important technical data may be contained in the envelop and tied thereto, giving information of value as to the strength of the powder charge, etc. This data is protected against tearing, soiling, etc., and due to the fact that the tabs are tied together, there is no danger of loss due 95 to the envelop opening by accident.

100 From the foregoing, taken in connection with the accompanying drawing, it will be seen that my invention is highly efficient and in every way desirable. Since probably the best results are obtained from the details dis- 105

closed they may well be followed, but within the scope of the invention as claimed numerous minor changes may well be made.

I claim:

- 5 An envelop adapted to be tied upon an article, said envelop having its ends provided with sealing flaps adapted to be folded onto and secured to one side of the envelop, and

tabs on the free ends of said flaps having eyes to receive the cord by means of which the envelop is tied upon the article, whereby to protect the envelop against opening.

In testimony whereof I have hereunto set my hand.

JOHN D. CARDINELL.
